CLAIM

The ornamental design for a sphere device on a cup, as shown and described.

DESCRIPTION

FIG. 1 is a perspective view showing the sphere device on a cup;

FIG. 2 is a front elevation view thereof;

FIG. 3 is a left side elevation view thereof, the right side elevation being the mirror image;

FIG. 4 is a top plan view thereof;

FIG. 5 is a bottom plan view thereof;

FIG. 6 is a front elevation view of a variation of the sphere device on a cup; and,

FIG. 7 is a left side elevation view thereof, the right side elevation being the mirror image.

The broken lines in the drawing views are included for the purpose of illustrating unclaimed environment only, and forms no part of the claimed design.

1 Claim, 3 Drawing Sheets(56)
